CHANGEABLE COLOR STRUCTURAL ELEMENT

Walter P. Berreski, Camden, N.J.

Application March 29, 1956, Serial No. 574,868

3 Claims. (Cl. 20—4)

The present invention relates to structural elements, and is concerned primarily with a structural element that is susceptible of having the color appearance which it offers changed by a simple mechanical operation.

At the present time, the modern housewife and home owner are color-conscious. Bathrooms and kitchens are often provided with two-tone color effects, and the housewife is often desirous of changing the color of either or both of the colored sections. Under present-day conditions, this involves a painting operation.

Then again, various articles such as kitchen cabinets, refrigerators, coffee tables, and other pieces of furniture are being offered to the public in different and varied colors, and the owner of such an article is often desirous of changing the color thereof. As above pointed out, this can be done only by a painting operation.

The present invention is founded on the belief that if certain structural elements are provided which are susceptible of having their color changed by a simple mechanical operation, the public will have been provided with something that fills a long-felt need.

With the foregoing conditions in mind, the present invention has in view as its foremost objective the provision of a structural element which consists essentially of two face plates, one of which is transparent or translucent, and between which is rotatably positioned a plurality of roller elements in close juxtaposition, with the roller elements presenting cylindrical surfaces each of which is divided into arcuate sectors of different colors. One of the face plates is formed with an access slot whereby a finger may be run along the roller elements in engagement therewith to cause a rotation thereof and bring different angular sectors of their cylindrical surface into effective position.

From the foregoing, it is apparent that such a structural element is adapted for use in a permanent building installation to provide one or more sections of a wall such as a bathroom or kitchen wall. When so employed, the parts are so arranged that the roller elements preferably are vertically disposed, and the access slot is provided along either a top or bottom edge, such as the edge adjacent to a floorboard. Thus, another important object of the invention is to provide a structural element of the character indicated in which the access slot is formed on the exposed face plate, and preferably along one edge thereof.

The invention also contemplates the use of the structural element hereof in certain articles of furniture, such as a coffee table, in which one face plate is ordinarily exposed, while the other face plate will be concealed, yet accessible. Thus, another highly important object of the invention is to provide a structural element of the character aforesaid which includes two face plates, one of which is intended to be exposed and the other concealed, with the access slot being formed at an appropriate location in the concealed face plate.

The whole idea back of the present invention is to provide for the easy changing of the color appearance which

2

is offered by the structural element. While it is possible, and entirely practical under certain conditions, to employ an exposed face plate that is substantially fully transparent, such as glass, the invention has in mind as a further object the provision of a structural element of the type aforesaid in which the exposed face plate is translucent rather than transparent, and has light-diffusing properties. When this type of exposed face plate is used, the individual outline of each roller member is obscured, and the entire element simply gives the effect of the particular color desired.

Still another object is to provide, in a structural element of the type noted, spaced face plates having inner surfaces that are corrugated or grooved to provide for accurate positioning of the roller elements. This feature is of importance, because it not only insures of the proper positioning of the roller elements, but also of their effective rotation, as the case demands.

Various other more detailed objects and advantages of the invention, such as arise in connection with carrying out the above-noted ideas in a practical embodiment, will in part become apparent and in part be hereinafter stated as the description of the invention proceeds.

The invention, therefore, comprises a changeable color structural element which consists essentially of a pair of spaced face plates having inner corrugated surfaces, and one of which is transparent or translucent. Operatively received in the corrugations between the plates is a plurality of roller elements presenting cylindrical surfaces, 30 arcuate sectors of which are of different colors. One of the face plates is formed with an access slot at a convenient location.

For a full and more complete understanding of the invention, reference may be had to the following description and accompanying drawing, wherein:

Figure 1 is a perspective view of a wall section that comprises the changeable color structural element of this invention.

Figure 2 is a detailed vertical section taken about on the plane represented by the line 2—2 of Figure 1, with parts broken away to permit illustration on an enlarged scale.

Figure 3 is a horizontal section taken on the plane represented by the line 3—3 of Figure 1.

Figure 4 is a detailed perspective of one of the roller elements, per se.

Figure 5 is a view in end elevation of one of the roller elements.

Figure 6 is an end elevation similar to Figure 5 of a modification in which three arcuate sectors are provided on the cylindrical surface of the roller element.

Figure 7 is a perspective of a table, the top of which comprises a structural element of this invention; and

Figure 8 is a detailed vertical section through a portion of the table shown in Figure 7, and is taken about on the plane represented by the line 8—8 of Figure 7.

Referring now to the drawings, wherein like reference characters denote corresponding parts, and first more particularly to Figures 1 to 6, inclusive, there is illustrated in Figure 1 a wall W that is intended to be a part of a permanent building installation such as a bathroom or kitchen wall. In accordance with the modern practice of providing two-tone effects, this wall W is shown as including an upper section A and a lower section B. The bottom of the wall is determined by a conventional floorboard 10.

To illustrate the application of the present invention, the bottom section B of the wall W takes the form of the structural building element provided by this invention. As shown in Figures 2 and 3, the wall section B comprises an outer exposed face plate 11 and an inner face plate 12 that ordinarily would be concealed or hidden. It is evident that only the exposed face plate

11 need have the transparent or translucent properties. In accordance with the present invention, these face plates 11 and 12 may be made from an appropriate glass, or any of the well-known plastic compositions which are now available to the public. Many of the cellulose acetates and vinyl chlorides will be found to be suitable. The important thing is that the exposed face plate 11 be either transparent or translucent.

The face plate 11 has an inner surface 13 that is spaced from a corresponding inner surface 14 on the plate 12. These surfaces 13 and 14 are formed with grooves 15 which provide, in effect, corrugated surfaces. The grooves 15 on one plate confront the grooves 15 in the other; and received in each pair of these complementary grooves is a roller element 16.

While it would be possible, and perhaps even practical, to form the roller element 16 of a shape other than a true cylinder, the invention has particularly in mind the use of a cylindrical roller element such as is shown in Figure 4. This roller element 16 has a cylindrical surface that is divided off into two sectors 17 and 18, each of substantially 180° extent, and which sectors are differently colored. Thus, the sector 17 of each roller 16 is of one color, while the sector 18 is of a different color. In any one structural element, all of the sectors 17 will preferably be of the same color, while all of the sectors 18 are of the same color that is different from that of the sectors 17.

As shown in Figure 3, the rollers 16 are preferably arranged in close juxtaposition so as to afford the maximum appearance effect possible for any particular color.

End pieces 19 maintain the assembled relation of the structural element. These end pieces 19 are shown as formed with flanges 20 that are received in correspondingly shaped notches formed along the outer edges of the plates 11 and 12. These end pieces 19 may be made from any appropriate material such as wood or metal, but the invention has particularly in mind the use of an appropriate plastic.

It is also notable that the roller element 16 may be either solid or tubular, and made from any material desired. If solid, they might be wood; if tubular, they would probably be of sheet metal or plastic.

Referring now more particularly to Figures 1 and 2, it will be noted that the exposed face plate 11 is formed with a slot 21, which, as shown in Figure 1, is located just above the floorboard 10. This slot affords access to the rollers 16 so that they may be engaged by the finger of an operator, as illustrated, and rotated to the angular extent required to bring the desired arcuate sectors of the rollers into effective visible position.

Referring now more particularly to Figures 7 and 8, the structural element of this invention is therein illustrated as being used as the top C of a table T. The latter includes four legs 22 which support the top C. As shown in Figure 8, the top C extends outwardly beyond the leg 22 at each corner.

The top C comprises an exposed face plate 23 and a hidden or concealed face plate 24. Between the plates 23 and 24 there are the usual rollers 16. The plates 23 and 24, together with the roller 16, are maintained in assembled relation by the usual end pieces 19 in the manner above described in connection with the form of invention illustrated in Figure 1. The important difference between the table top C and the wall section B is that in the table top C the hidden or concealed plate

24 is formed with a slot 25 which affords access to the roller 16. Thus, a person may place his fingers underneath the table where the slot 25 is located, and run them along the rollers and rotate them to the extent required to bring the desired arcuate sectors into effective position.

A slightly modified form of roller is depicted in Figure 6. This roller, which is identified as 26, has a cylindrical surface that is divided into three sectors 27, 28, and 29, each of which has an angular extent of 120°. The sector 27 is of one color; the sector 28 of another color; and the sector 29 is of still another color. Thus, with either of the structural elements B or C including rollers 26, three color effects are provided.

While preferred specific embodiments of the invention are hereinbefore set forth, it is to be clearly understood that the invention is not to be limited to the exact constructions, materials, and designs illustrated and described, because various modifications of these details may be provided in putting the invention into practice within the purview of the appended claims.

What is claimed is:

1. In a changeable color structural element, a pair of face plates one of which is translucent and having inner surfaces in spaced relation formed with confronting parallel grooves, a plurality of cylindrical roller elements rotatably received in said grooves, each of said roller elements having a cylindrical surface including two sectors of different colors, end pieces maintaining said plates and rollers in assembled relation, and a slot formed in one of said plates affording access to the rollers to provide for the rotation thereof.

2. In a permanent building installation, a wall section comprising a hidden plate, a translucent exposed face plate spaced from said hidden plate, said plates having inner surfaces formed with confronting parallel grooves, a plurality of roller elements rotatably received in said grooves, each of said roller elements having a cylindrical surface including two differently colored angular sectors, end pieces maintaining said plates and roller elements in assembled relation, and a slot in said exposed face plate providing access to the rollers.

3. In a table, a top comprising a hidden plate, a translucent exposed face plate spaced from said hidden plate, said plates having inner surfaces formed with confronting parallel grooves, cylindrical roller elements rotatably received in said grooves, each of said roller elements having a cylindrical surface divided into differently colored angular sectors, end pieces maintaining said plates and roller elements in assembled relation, and an access slot formed along one edge of said hidden plate.
